US00D838594S

(12) **United States Design Patent** (10) **Patent No.:** **US D838,594 S**
(45) **Date of Patent:** **** Jan. 22, 2019**

(54) **LID**

(71) Applicant: **William Connolly Ainsworth, Jr.**,
Madisonville, KY (US)

(72) Inventor: **William Connolly Ainsworth, Jr.**,
Madisonville, KY (US)

(73) Assignee: **William Connolly Ainsworth, Jr.**,
Madisonville, KY (US)

(**) Term: **15 Years**

(21) Appl. No.: **29/620,933**

(22) Filed: **Aug. 25, 2017**

(51) **LOC (11) Cl.** **09-07**

(52) **U.S. Cl.**
USPC **D9/454; D9/445**

CLAIM

The ornamental design for a lid, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark office patent file or records, but reserves all other copyrights whatsoever. FIG. 1 is a top isometric view of a lid, showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a bottom isometric view thereof.
